UNITED STATES PATENT OFFICE.

JOSEPH C. F. DICK, OF BELVIDERE, ILLINOIS.

BUTTON-ATTACHING MACHINE.

SPECIFICATION forming part of Letters Patent No. 354,969, dated December 28, 1886.

Application filed November 11, 1885. Serial No. 182,487. (No model.)

To all whom it may concern:

Be it known that I, JOSEPH C. F. DICK, of Belvidere, in the county of Boone and State of Illinois, have invented certain new and useful Improvements in Machines for Attaching Buttons to Wearing-Apparel; and I do hereby declare that the following specification, taken in connection with the drawings furnished and forming a part of the same, is a clear, true, and complete description of my invention.

My said improvements are applicable to such machines as force the prongs of a fastener into and through a fabric and clinch them, while said fastener is coupled to a button, and is suspended from a slotted holder or jaw with which a clinching-jaw co-operates. Whether said prongs are forced into a fabric or the latter forced against said prongs, it is essential for obtaining good results that the prongs should stand as nearly as possible at right angles to the face of the jaw by which the button and fastener are held; but machines of this class have heretofore been so organized that they fail in properly holding the prongs, and frequently cause them to be crippled or bent during the initial portion of the puncturing operation; and for obviating this difficulty I have, as I believe, for the first time devised a prong-adjusting finger, and have so organized it with said jaws that it automatically causes the prongs to stand at right angles to the face of the holding-jaw, and maintains them in that position during the initial puncturing operation without obstructing the movement of the clinching-jaw; and said prong-adjusting finger is also arranged to retire from said holding-jaw for enabling a fastened button to be detached therefrom and leave the jaw free to receive another button and its fastener.

One form of machine to which my said improvements are applicable is shown and described by me in my Letters Patent No. 310,934, dated January 20, 1885.

To more particularly describe my invention, I will refer to the accompanying drawings, in which Figures 1 and 2, in side and end views, illustrate so much of my prior patented machine as is deemed necessary with my present improvements applied thereto. Figs. 3 and 4 illustrate the prong-adjusting finger, and the holding-jaw detached, in its operative and its inoperative position. Figs. 5 and 6, in two views, illustrate my prong-adjusting finger as

applied to a machine of slightly-different construction.

55

In the machine shown in Figs. 1 and 2 the frame or standard A, the treadle B, coupled by a link, a, to the rear end of the pivoted clinching-jaw C, having thereon a clinching-die, b, are all substantially as shown in my said Letters Patent.

The head D, with its inclined chute or race-way E, slotted longitudinally, as at e, and having a downwardly-projecting rib, d, (at one side of said slot, for partially controlling a fastener, f, engaged with the eye e of a button,) and also having a foot or slotted holding-jaw, as at g, a stop-spring, i, and feeding-finger k, (operated by crank-lever l and vertical arm m and cord n,) are also all substantially as shown in said patent. The button-lifting spring h is also as in my prior machine, and on this I have heretofore relied for firmly holding the button and fastener in the holding-jaw; but it could not reliably control the pendent prongs of the fastener, but would sometimes permit said prongs to stand at such an angle to the face of the holding-jaw as resulted in their being crippled and bent during the puncturing operation. I still use this lifting-spring for properly holding the button; and it also co-operates with the novel prong-adjusting finger F in controlling the fastener, although said adjusting-finger is of value in combination with jaws which do not have said lifting-spring.

In this machine said prong-adjusting finger consists of a thin flat plate, o, and a bell-crank lever, p, having a pendent arm to which said plate is attached. This bell-crank lever is pivoted to the head D at p', so as to vibrate in a vertical plane and to move said plate toward and from the slot e, and at right angles thereto and beneath the foot of the chute at g, which constitutes the upper jaw of the machine. The proper vibratory movement of said plate along the face of said upper jaw is derived from the vertical arm m and the retractile spiral spring p', it being obvious that when the treadle is freed and actuated by its spring a' the contact of said arm with said lever will cause the plate o to be moved away from the slot e, and that when said treadle is next depressed for lifting the lower jaw said plate will be thrown forward by the spring p'.

In Fig. 4 a button, e, and fastener f are shown,

with the prongs of the latter inclined, as at any time liable, when said prong-adjusting finger is not used, and in Fig. 3 said finger is shown in its working position after it has rectified the position of the prongs and while it is holding said prongs preparatory to the rise of the lower jaw. In order that said finger may not obstruct said lower jaw during its clinching operation, the under surface of the 10 foot of the chute which forms the upper jaw is cut away or recessed at one side equal to the thickness of the plate o , and hence the latter, when it occupies said recess, presents its under or outer surface in the same plane as 15 the surface of the upper jaw at the opposite side of the slot, and in substance is a part of said jaw.

It will be seen that the prong-adjusting finger need not have a movement toward and from 20 the slot of more than, say, one-sixteenth of an inch, and that it is wholly immaterial what position said finger may assume when withdrawn from contact with the prongs of the fastener, so long as said finger permits the 25 fastened button to be moved outwardly from the slot of the jaw and another button and its fastener to enter and properly occupy said jaw.

It will be obvious in a machine having a lower jaw otherwise organized and operated, 30 or a feeding-finger otherwise operatively connected with the treadle, that my novel prong-adjusting finger need only be so far varied in its form or construction or arrangement as to properly harmonize with said other variations— 35 as, for instance, in Figs. 5 and 6, I show a machine in which the lower or clinching jaw, C , is vertically reciprocated upon and with a rod, C' , lifted by the treadle B , and the feeding-finger k is mounted on a rock-shaft, k' , which 40 is coupled to the rod C' by a link, k^2 , and hence the prong-adjusting finger F is of slightly-different form and in slightly different arrangement, and it is thrown forward by its spring p^2 , as in the other machine, but it is thrown 45 rearward by means of an arm, g , projecting from the rock-shaft k' . In both instances the prong-adjusting finger is provided with means whereby its vibrations can be varied.

In Fig. 1 the upper arm of the bell-crank 50 lever p has at its outer end an adjusting-screw, r , tapped into a longitudinal hole in said arm, which serves as a variable abutting-surface for contact with the swinging arm m . In Figs. 5 and 6 a similar screw, r , is tapped 55 into a hole through the upper arm of the bell-crank lever p , so that its point or tip serves as a variable abutment against the surface of the arm g .

It will be obvious, while it is in every 60 way preferable to have the prong-adjusting finger forced toward the prongs with a yielding pressure, as by its spring p^2 , that a spring can be relied upon for withdrawing the finger, and the arm m or g can then be arranged 65 to force the finger forward, in which case either arm of the lever, if made slender and of spring metal, would afford the desired

yielding pressure; or if made rigid the adjusting-screws would enable such precise adjustments of vibration by the finger as to fairly 70 compensate for its lack of resiliency.

It must not be supposed that it is essential that the operative portion of the finger F should move in the arc of a circle, or that it should of necessity remain in contact with the prongs 75 of a fastener during the clinching operation, although this is desirable. The main end to gain in this connection is the proper holding of the prongs during the initial puncturing operation, because when once rightly started 80 into a fabric said prongs have but little, if any, tendency to objectionable deflection. As to the lifting-spring h , it will be seen that if it be not employed the prong-adjusting finger will still assure the proper position of the 85 prongs; but it is obvious that with said spring the adjusting-finger is all the more effective, because in forcing the prongs from their inclined to their proper position said spring is more or less strained, and as a result the button and its fastener is held much firmer in the 90 upper jaw than would be the case if the spring h were used alone.

Having thus described my invention, I claim as new and desire to secure by Letters Patent— 95

1. The combination, substantially as hereinbefore described, of the slotted jaw for holding a button, with its pronged fastener projecting therefrom, the clinching-jaw, and the vibrating prong-adjusting finger which moves 100 along the face of said slotted jaw for engaging with the prongs of a fastener and holding them, during the operation of the clinching-jaw, in a position favorable to puncturing a fabric without bending or crippling. 105

2. The combination of the slotted jaw having a button-lifting spring therein, the clinching-jaw, and a vibrating prong-adjusting finger which moves to and fro along the face of the slotted jaw, at one side of its slot and at 110 right angles thereto, substantially as described. 115

3. The combination of the clinching-jaw, the slotted jaw having a recess at one side of the slot, and a vibrating prong-adjusting finger which occupies said recess when the jaws 115 are forced together, substantially as described.

4. The combination, with the slotted holding-jaw and the clinching-jaw, of a vibrating prong adjusting and holding finger provided with an adjustable abutment, substantially as 120 described, whereby the movements of said finger may be varied.

5. The combination, with the slotted holding-jaw and the clinching-jaw, of a vibrating prong-adjusting finger forced toward said holding-jaw by a spring, substantially as described, whereby said finger will engage with the prongs of a button-fastener under a yielding pressure. 125
